UNITED STATES PATENT OFFICE.

EDWARD B. LARKIN AND THOMAS A. CONNEELY, OF BRADFORD, PENNSYLVANIA.

FIRE EXTINGUISHER.

Application filed April 14, 1928. Serial No. 270,031.

The invention has broad reference to fire extinguishing means, such as is particularly adapted to be incorporated in tanks and containers, for crude, oil, gasoline, naptha, benzine, and all other inflammable liquids, and it has more particular reference to a self adjusting distributing device for the various foam extinguishing compounds which are now used for this purpose.

10 From the foregoing, it will be evident that it is now a matter of common knowledge that foam extinguishing compounds are reasonably effective for extinguishing fire in containers and tanks of the type specified.

15 At the present time, it is the practice to equip the tank with a nozzle at the top through which the compound is introduced to blanket the surface of the fluid and to smother the fire. Owing to the change of level of

20 the fluid in the tank, it is obvious that under certain conditions, the distance between the nozzle and the fluid level is comparatively great, and when the foam extinguishing compound is injected through the nozzle, it frequently loses its effectiveness when allowed to drop a great distance down onto the surface of the fluid.

25 It is thought that this is because the liquid constituents separate before coming into contact with the burning fluid.

30 The objectionable condition thus referred to can be remedied through the utilization of a device which more effectively flows or feeds the compound onto the surface of the liquid, and it is my idea to provide a self adjusting feeding and distributing device for this purpose which is located inside of the tank and which includes a floating spreader which follows the liquid level.

35 In the drawings:

Figure 1 represents an elevational view with a portion of the tank broken away to expose the device on the inside thereof.

Figure 2 is a top plan view with portions broken away and shown in section.

Figure 3 is a fragmentary detail sectional view showing the adjustable portion of the delivery conduit.

Figure 4 is a view in section and elevation showing the ball float, adjustable conduit, flared discharge nozzle, and guiding means for the float.

The numeral 1 designates an ordinary tank, containing inflammable liquid 2. Inside of

guide rods 3. Arranged between these is a ball float and spreader 4, rigidly connected with a pair of downwardly diverging arms 5.

These arms have their lower ends directed outwardly at right angles as at 6 and provided with guide sleeves 7, slidably mounted on the guide rods 3. The arms 5 connect with the lower end of a telescopic discharge conduit 8. This is made up of sections 9, 10, 11, 12, and 13. The section 13 constitutes a discharge nozzle and is provided with a flared end 14 located over the top of the floating spreader 4. This telescopic or extensible conduit is connected with an inverted cup 15 on the upper end of the compound supply pipe 16. The pipe 16 may be of any suitable configuration and may be either on the inside or outside of the tank.

In practice, it is obvious that the foam extinguishing compound is supplied from a suitable source and conveyed through the delivery pipe 16, where it is elevated to a point adjacent the center of the top of the tank 1. It then drops down through the self ejecting discharge conduit 8 and nozzle 13 onto the surface of the floating ball 4. This ball always follows the liquid level and is thereby properly positioned for flowing and spreading the compound evenly and in an intact manner over the burning surface of the liquid 2 in the event of fire.

It is submitted that the apparatus prevents the separation of the liquid constituents from the foam before and when it comes into contact with the burning fluid, more especially when the tank is only partly filled.

Moreover, the device is self and ever set thus rendering it substantially automatically adjustable. The relationship of parts is such as to insure proper and uniform distribution.

It is believed that by considering the description in connection with the drawings, a clear understanding of the construction, operation and advantages of the invention will be had. Therefore, a more lengthy description is regarded unnecessary.

Minor changes coming within the field of invention claimed may be resorted to, if desired.

We claim:

1. In a structure of the class described, in combination, an inflammable liquid container, a foam compound feeding pipe discharging into the interior of the top portion of said

container, adjustable delivering and feeding means associated with the discharge end of the feed pipe, said feed means comprising an adjustable discharge conduit and a floating ball located beneath the discharge end thereof.

2. A device of the class described comprising spaced guide members, a telescopic discharge conduit located therebetween, a ball 10 float located between the guide members and beneath the discharge end of the conduit, and connections between the conduit and float and guide members.

3. A device of the class described comprising a feed pipe for conducting and elevating a foam extinguishing compound, a depending telescopic discharge conduit connected with the discharge end of said feed pipe, and a floating ball spreader fixedly con-

nected with and located beneath the discharge 20 conduit.

4. A device of the class described comprising a feed pipe for conducting and elevating a foam extinguishing compound, a depending telescopic discharge conduit connected 25 with the discharge end of said feed pipe, and a floating ball spreader fixedly connected with and located beneath the discharge conduit, together with guide means and a pair of 30 standing guide arms connected with said conduit, and provided with guide sleeves mounted on said guide means, said arms being fastened to diametrically opposite sides of the ball float.

In testimony whereof we affix our signatures.

EDWARD B. LARKIN.
THOMAS A. CONNEELY.
